UNITED STATES PATENT OFFICE.

CHARLES S. DEMAREST, OF BROOKLYN, NEW YORK, ASSIGNOR TO AMERICAN TELEPHONE AND TELEGRAPH COMPANY, A CORPORATION OF NEW YORK.

REPEATER-CONTROLLING SYSTEM FOR FOUR-WIRE TELEPHONE-CIRCUITS.

1,381,545.

Specification of Letters Patent. Patented June 14, 1921.

Application filed September 16, 1919. Serial No. 324,155.

To all whom it may concern:

Be it known that I, CHARLES S. DEMAREST, residing at Brooklyn, in the county of Kings and State of New York, have invented certain Improvements in Repeater-Controlling Systems for Four-Wire Telephone-Circuits, of which the following is a specification.

This invention relates to repeater controlling systems for four-wire telephone circuits, and more particularly to means to prevent the connection of the repeater elements with the said four-wire circuit until the four-wire circuit is connected with a telephone line in each direction and certain predetermined keys associated with the cord circuits are in their normal positions.

In the operation of the four-wire telephone circuits having repeater elements associated with each of the two-wire sides of the circuit, it is well known that such circuits will tend to sing unless the four-wire circuit is connected by means of a cord circuit with a telephone circuit in each direction with which it is intended to coöperate and all of the keys except the monitoring key of each cord circuit are in their normal positions. Singing of a repeater circuit arises from the unbalanced condition of the circuit which exists prior to the establishment of the through-line connection. As is well known, the repeater elements associated with such four-wire circuits are operated to give a gain of sufficient magnitude to overcome the loss not only in the four-wire circuit itself, but also the loss introduced by the cord circuits and the telephone line circuits with which repeater circuit is intended to coöperate.

One of the objects of this invention is to provide means whereby the repeater elements which are normally disconnected from the two-wire sides of the four-wire circuits may be effectively connected with the said circuit only when the four-wire circuit is connected with a telephone line circuit in each direction and certain predetermined keys of the cord circuits are in their normal unoperated positions.

Another object of this invention is to provide means for connecting the filament heating batteries with the filaments of the thermionic repeater elements only when the repeaters themselves are connected with the four-wire circuit.

In my co-pending application, Serial Number 278,945, filed February 24, 1919, a

means is described for accomplishing this result which involves the use of marginal relays associated with the sleeve contacts of the jacks of the four-wire circuit. This invention differs from that described in the pending application in the avoidance of the use of marginal relays and in accomplishing the desired result by means of a simplex circuit over the tip and ring sides of the four-wire circuit and its associated cord circuits.

Other objects of this invention will appear from the following description when read in connection with the attached drawing, Figure 1 of which shows a typical toll cord circuit and Fig. 2 shows the four-wire circuit with which the cord circuit is adapted to coöperate.

The toll cord circuit shown in Fig. 1 terminates in plugs P_1 and P_2 , plug P_1 being adapted for insertion in jacks J_1 and J_2 , thereby connecting lines L_1 and L_2 with said cord circuit, and plug P_2 being adapted to be inserted in jacks J_3 and J_4 of the four-wire circuit shown in Fig. 2, thereby connecting the four-wire circuit with the said cord circuit. Lines L_1 and L_2 extend from the toll office A to an ordinary central office and they may be either ringdown or call-circuit trunks. Associated with the cord circuit are keys K_1 , K_2 , K_3 and K_4 ,—key K_1 being adapted to apply ringing current to the lines L_1 and L_2 ; key K_2 being a splitting key of the well known type; K_3 when operated toward the left being adapted to connect the operator's telephone set with the cord circuit for talking purposes, and when operated toward the right to connect the telephone set for monitoring purposes; and key K_4 being adapted to apply ringing current to the circuit with which the plug P_2 may be connected. An impedance coil, 1, is bridged across the tip and ring sides of the cord circuit and the midpoint of the said coil is connected to conductor 2, which, may be grounded either by the operation of keys K_1 , K_2 , K_3 (talking side), and K_4 , or by the operation of the relay R_1 which is connected with the sleeve of plug P_1 . Bridged across the circuit are the supervisory relays R_2 and R_3 , which respond to signaling current received over the lines with which the said cord circuit may be connected.

Fig. 2 represents a four-wire circuit extending between two toll offices designated A

and B and terminating in jacks J_3 and J_4 at office A and jacks J_5 and J_6 at office B. Jacks J_3 and J_4 are adapted for connection with the toll cord shown in Fig. 1 by the insertion of the plug P_2 in either of said jacks. Jacks J_5 and J_6 at office B are, in like manner, adapted to be connected to another toll cord similar in every respect to that shown in Fig. 1 by the insertion in the said jacks of a plug similar to plug P_2 . The four-wire circuit shown in Fig. 2 consists of two two-wire sides, 3 and 4, with which are associated repeater elements 5 and 6 respectively. These elements are shown in the figure as being the well known thermionic devices, but it is to be understood that any well known type of telephone repeater might be substituted in place thereof.

These two-wire sides are electrically regulated by means of the triple winding transformers X and Y, with which are associated net works N_1 and N_2 respectively, which are adapted to balance the telephone lines connected with the four-wire circuit at offices A and B respectively. The function of net works N_3 and N_4 , which are connected with the two-wire terminals at offices A and B respectively, is to regulate the transmission gain produced by the repeater circuit so that the transmission equivalent over all through-line connections will be substantially the same. Relay R_4 , which is bridged across one of the two-wire sides at office A, is responsive to ringing current transmitted over the said side from office B to office A and co-operates with relay R_5 to produce a signal at office A by the lighting of the lamp S_1 . A relay R_6 , similar to R_4 , co-operates with relay R_7 at office B to produce a signal at office B by the lighting of the lamp S_2 .

It will be noticed that the repeater elements 5 and 6 are normally disconnected from the sides of the four-wire circuit. Switching relays R_8 and R_9 , when operated serve to connect the repeater element 5 with the two-wire side 3, and switching relays R_{10} and R_{11} serve in a similar manner to connect the element 6 with the two-wire side 4, and their operation is controlled by the joint operation of relays R_{12} and R_{13} . Relay R_{14} , which is associated with the repeater elements, is adapted to connect the batteries B_1 and B_2 with the filaments of the repeater elements 5 and 6 respectively. At office A relays R_{15} and R_{16} associated with the sleeve contacts of jacks J_3 and J_4 respectively, and, in like manner, at office B relays R_{17} and R_{18} associated with jacks J_5 and J_6 respectively, are adapted to control the operation of relays R_{12} and R_{13} which, in turn, serve to control the operation of the switching relays. Relays R_{19} and R_{20} , at office A and office B, respectively, referred to hereafter as the "guard relays," serve to prevent the operation of the control relays R_{12} and R_{13} after

the cord circuits have been connected with the jacks at offices A and B and prior to the time of completion of the through-line talking connection.

This invention will be more fully understood from the following description of its mode of operation. Assuming, for example, that a signal has been received at office A over line L_1 , the operator inserts plug P_1 in jack J_1 of line L_1 and, by moving key K_3 to the left, learns from the other operator at the distant end of line L_1 that a circuit connection is desired which necessitates the use of the four-wire circuit extending between toll offices A and B. The operator A thereupon inserts plug P_2 of her cord circuit in the jack J_3 of the four-wire circuit, and, by operating ringing key K_4 , applies ringing current to the four-wire circuit, thereby causing the operation of relays R_6 and R_7 and, in consequence thereof, the lighting of the lamp S_2 . The operator at B inserts a plug similar to plug P_2 of the cord circuit shown in Fig. 1 and by operating a key similar to key K_3 she is enabled to talk with the operator at office A who has maintained key K_3 in its talking position. Upon receiving the proper instructions from the operator at office A the operator at office B thereupon inserts the other plug of the cord circuit in a jack of a trunk line which may be assumed to be of a type similar to line L_1 . The operator at office B then advises the other operator at the distant end of the trunk line with which she has connected her cord circuit to establish the connection with the desired subscriber's telephone.

When the operator at office A inserts the plug P_2 in jack J_3 a circuit is established from battery B_3 over the sleeve contacts of the said plug and jack and the winding of relay R_{15} to ground, thereby causing the operation of the said relay, which grounds conductor 7 by the closing of the upper contact 8 of said relay. Practically simultaneous with the establishment of the circuit just outlined, another circuit is established from battery B_4 , winding of relay R_{16} and conductor 9 to the midpoint of the impedance coil 10, thence over the tip and ring sides of the two-wire terminal of the four-wire circuit and the tip and ring contacts of jack J_3 and plug J_2 to the impedance coil 1, and thence over conductor 2 and contact 11 of key K_3 to ground, which causes the operation of relay R_{19} , and prevents the establishment of a circuit from battery B_5 , winding of relay R_{12} , thence to the midpoint of winding 18, and over the two wires in parallel to the midpoint of winding 14, thence through conductor 12, contact 15 of relay R_{19} , and conductor 7, to ground. After the plug P_2 is inserted in either jack J_3 or J_4 , the guard relay R_{19} will be operated by the flow of current over a simplex cir-

cuit established by the impedance coils 10 and 1 whenever conductor 2 is grounded, which may occur whenever keys K_1 , K_2 , K_3 (talking side), and K_4 are operated and as long as plug P_1 remains disconnected from the jack of the trunk line with which it is intended to coöperate. In a similar manner, the guard relay R_{20} at office B will be operated whenever the similar keys of the cord circuit at office B are operated and until the plug of the cord circuit is connected with the trunk line with which it is intended to coöperate. It will be seen that the function of the guard relays R_{19} and R_{20} is to delay the operation of relays R_{12} and R_{13} which control the means to connect the repeater elements with the four-wire circuit, until the conditions are right for conversation between subscribers at the opposite ends of the through-line connection.

Let it be assumed that a complete through-line connection has been established between the two subscribers so that further supervision on the part of the operators is unnecessary. When this occurs all keys of each cord circuit will be restored to their normal positions, thereby removing the ground from the simplex circuit and releasing the guard relays R_{19} and R_{20} at offices A and B respectively. As soon as relay R_{19} is released the circuit heretofore described extending from battery B_5 and winding of relay R_{12} to ground over contact 8 of relay R_{15} , will be established, thereby causing the operation of relay R_{12} . In a similar manner relay R_{13} will be operated by current flowing from battery B_6 through winding of relay R_{13} and over a circuit to ground through contact 16 of relay R_{17} .

As soon as relays R_{12} and R_{13} are jointly operated, their contacts 17 and 18 are closed and a circuit is established from ground over the said contacts, thence over conductors 19, 20, 21, and 22, to the switching relays R_8 , R_9 , R_{10} and R_{11} respectively, thereby causing the operation of the said relays, which results in the effective connection of the repeater elements 5 and 6 with their respective sides of the four-wire circuit. Furthermore, relay R_{14} is operated by the closing of contacts 17 and 18 which connects batteries B_1 and B_2 with the filaments of the repeater elements 5 and 6 respectively, so that the elements will begin to function properly.

It will be apparent from the foregoing description that by means of this invention the control of the connection of telephone repeaters with the sides of a four-wire circuit will be automatic and dependent upon conditions within each cord circuit adapted to connect each end of the four-wire circuit with a trunk line circuit. The means for effecting such control consists in a guard relay or equivalent device which, when op-

erated, delays the operation of the switching relays adapted to connect the repeater elements with the four-wire circuit until the cord circuits are in proper condition for conversation between subscribers at the opposite ends of through-line circuit. The guard relay may be operated by a flow of current due either to the operation of certain keys of the associated cord circuit or to the non-association of the opposite plug of the cord circuit with the jack of the trunk line circuit with which it is intended to coöperate. Furthermore the path of the current that operates the said guard relay is, in part, a simplex circuit over the tip and ring sides in parallel of the two-wire terminal of the four-wire circuit and of the cord circuit associated therewith.

Although this invention has been shown as embodied in a certain form, it is apparent that it is capable of embodiment in other and different forms within the scope of the appended claims.

What is claimed is:

1. In a signaling system, the combination of a four-wire transmission circuit comprising two two-wire side circuits electrically related by means of transformers, a repeater element adapted to be connected with each side circuit, switching means to effect such connection and means for controlling said switching means comprising a relay controlled by the flow of current over a circuit simplex upon the two-wire terminals of the four-wire circuit and the associated cord circuit whereby said switching means may be prevented from connecting said repeater elements with the side circuits of the four-wire circuits.

2. In a signaling system, the combination of a four-wire transmission circuit comprising two two-wire sides electrically related by means of transformers, cord circuits adapted for connection with each end respectively of said four-wire circuit, a repeater element adapted for connection with each of the two two-wire sides of said transmission circuit and normally disconnected therefrom, switching means to connect said repeater elements with said sides and means for controlling said switching means comprising a relay individual to and electrically connected with each side of the four-wire circuit and governed by the connection of its respective cord circuit with the four-wire circuit and by the relative positions of the keys associated with the said cord circuit.

3. In a signaling system, the combination of a four-wire transmission circuit having a plurality of repeater elements associated therewith and normally disconnected therefrom, switching means adapted to connect said repeater elements with said four-wire circuit, cord circuits adapted to connect each

- end of said four-wire circuit with a telephone trunk circuit, an impedance coil bridged across the sides of said cord circuits and another impedance coil bridged also 25
- 5 across the sides of each of the two-wire terminals of said four-wire circuit whereby simplex circuits are established for controlling the operation of said switching means.
- 10 4. In a signaling system, the combination of a four-wire transmission circuit having a plurality of repeater elements associated therewith and normally disconnected therefrom, switching means adapted to connect 30
- 15 said repeater elements with said four-wire circuit, cord circuits adapted to connect each end of said four-wire circuit with a telephone trunk circuit and means to control the operation of said switching means normally governed by the connection of said 35
- 20 cord circuits with each end of the four-wire

circuit and prevented from operating until the opposite end of each of the said cord circuits is connected with its associated trunk circuit.

25

5. In a signaling system, the combination of a four-wire transmission circuit having a plurality of repeater elements associated therewith and normally disconnected therefrom, a group of switching relays associated 30

with each side of said four-wire circuit adapted to connect said repeater elements with the respective sides, and a relay individual to each side and controlled by the connection of its respective cord circuit with 35

the four-wire circuit whereby the operation of said switching relays may be controlled.

In testimony whereof, I have signed my name to this specification this 12th day of September, 1919.

CHARLES S. DEMAREST.
